Primary Examiner—Carmen H. Vales-Lado**[57] CLAIM**

The ornamental design for a lidded beach table with interior recessed cup holders, as shown and described.

DESCRIPTION

FIG. 1 is a front elevational view of the lidded beach table with interior recessed cup holders showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top perspective view with the lid open.

The showing of the ground support broken away throughout the views indicates indeterminate length.
